UNITED STATES PATENT OFFICE.

HORACE WYMAN AND ALFRED F. MORELL, OF WORCESTER, MASSACHUSETTS,
ASSIGNORS TO CROMPTON & KNOWLES LOOM WORKS, A CORPORATION OF
MASSACHUSETTS.

WEFT-REPLENISHING LOOM.

1,150,477.

Specification of Letters Patent. Patented Aug. 17, 1915.

Application filed November 5, 1913. Serial No. 799,390.

To all whom it may concern:

Be it known that we, HORACE WYMAN and ALFRED F. MORELL, citizens of the United States, both residing at Worcester, in the 5 county of Worcester and Commonwealth of Massachusetts, have jointly invented certain new and useful Improvements in Weft-Replenishing Looms, of which the following is a specification.

10 Our invention relates to a weft replenishing loom, and more particularly to that type of weft replenishing loom provided with shuttle changing mechanism for changing shuttles, and substituting a new shuttle 15 containing a full bobbin, for the active shuttle containing a substantially exhausted bobbin.

Our invention particularly relates to improvements in the shuttle changing mechanism of looms of the type referred to, and more particularly to improvements in the type of loom shown and described in U. S. Letters Patent, No. 614,369, dated November 15, 1898.

25 In our improvements, a shuttle holder or magazine is provided, in which are placed a number of shuttles, to be fed or carried, when required, in a shuttle holder, which is held in its forward inoperative position, until the 30 substantial exhaustion of filling in the active shuttle is indicated by the feeler at the opposite end of the loom, when the shuttle changing mechanism is called into operation, on the next forward movement of the 35 lay, and the shuttle box, mounted on the lay and containing the active shuttle with the substantially exhausted bobbin therein, is raised to its upper inoperative position, allowing the shuttle holder, with a fresh shuttle 40 and a full bobbin, to be brought into alinement with the race-way, and said shuttle picked through the shed in the usual and well known way. On the backward movement of the lay, the shuttle having the substantially 45 exhausted bobbin is ejected through an opening in the rear of the shuttle box.

The back of the shifting shuttle box is fixed on the lay, and when the box is raised 50 to its upper position, as the lay is approaching its backward movement, the shuttle is raised above the fixed back, leaving the shuttle free to be discharged upon the receiving platform. The fixed back also serves for the

spare shuttle holder, as it assumes the position of the shifting shuttle box raised above it, when the spare shuttle is first picked across the lay.

Our invention consists in certain novel features of construction of our improvements as will be hereinafter fully described.

We have shown in the drawings portions of a loom of the type referred to, and patented in U. S. Letters Patent No. 614,369, above referred to, with our improved shuttle changing mechanism combined therewith, sufficient to enable those skilled in the art to understand the construction and operation thereof.

Referring to the drawings:—Figure 1 shows one end of the loom frame, and our improved shuttle mechanism, and other parts, connected therewith. Fig. 2 is an end view, corresponding to Fig. 1, showing some of the parts in a different position, and some of the parts connected with the magazine left off. Fig. 3 is a front view of the magazine mechanism, looking in the direction of arrow *a*, Fig. 1. Fig. 4 is, on an enlarged scale, a sectional view on line 4, 4, Fig. 3, looking in the direction of arrow *b*, same figure, with a part of the magazine broken away. Fig. 5 corresponds to Fig. 4, but shows some of the parts in a different position, and some of the parts are left off in this figure. Fig. 6 is a detached view of some of the magazine operating levers. Fig. 7 is, on an enlarged scale, a front view of the magazine stand and operating mechanism, looking in the direction of arrow *a*, Fig. 1. Fig. 8 is a plan view of the giveaway lever mechanism, looking in the direction of arrow *c*, Fig. 1. Fig. 9 is a plan view of the box operating motion, looking in the direction of arrow *c*, Fig. 1. In this figure the main driving gear is shown. Fig. 10 is a section, on line 10, 10, Fig. 9, looking in the direction of arrow *d*, same figure. Fig. 11 is a detached view of the lay end, with a removable shuttle box mounted thereon, looking in the direction of arrow *a*, Fig. 1, and illustrating a pivotally mounted and movable binder finger on the protector rod. Fig. 12 corresponds to Fig. 11, but shows the shuttle box in its raised position, and the shuttle carrier in its alined position; the shuttle is shown as being picked across the lay. Fig. 13 is a section, on line 13, 13,

Fig. 11, looking in the direction of arrow *e*, same figure, and, Fig. 14 is a section, on line 14, 14, Fig. 12, looking in the direction of arrow *f*, same figure.

- 5 In the accompanying drawings, 1 is the end frame or loom side, having fast thereon a stand 2, see Fig. 1, to which is adjustably secured by bolts 3', see Fig. 3, a stand 3, which supports the magazine 4.
- 10 Loosely mounted in bearings 3" and 3" on the stand 3, is a rod 5, see Fig. 7. On the outer ends of the rod 5 are secured by set screws 6, the hubs 7' of the levers 7, which levers have elongated openings 7" at their outer ends. Also secured on the rod 5, by a set screw 8", is the hub 8' of a finger 8, which finger is held in its outward position, see Figs. 5 and 6, by a torsion spring 9, see Fig. 7. The spring 9 encircles the rod 5 and has one end secured to the hub 3''' on the stand 3, and the other end secured to a collar 10, secured on the rod 5 by a set screw 10'.
- 15 A stud 11 is secured by a set screw 3'a' in the hub 3''' on the stand 3, see Fig. 7, and has pivotally mounted thereon the hub 12' of a lever 12. Secured on the upper part of the lever 12 is a stud 13', which has loosely mounted thereon a finger 13, see Fig. 6.
- 20 The stud 13' engages with the elongated opening 7" in a lever 7. Loosely mounted on a stud 14', secured to the stand 3, is a roll 14, see Fig. 5, over which roll the finger 13 is guided. Secured by a set screw 3'b' in
- 25 the hub 3'' on the stand 3, is a stud 15, which stud has pivotally mounted thereon the hub 16' of a lever 16, see Fig. 7. Secured on the lower part of the lever 16 is a stud 17', which has loosely mounted thereon a finger 17. The stud 17' engages an elongated opening 7" in the lever 7. Loosely mounted on
- 30 the stud 18', secured to the stand 3, is a roll 18, see Fig. 5, over which roll the finger 17 is guided.
- 35 19 is a stand secured to the magazine stand 3, in this instance by the bolt 19', see Fig. 4. Adjustably secured in the stand 19 is a stud 20, on which is loosely mounted the hub 21' of a lever 21, which is operated by an
- 40 upright bar 22, to which is secured, by bolts 23', the shuttle holder 23. The shuttle 4' is held in place in the holder 23 by a spring 24.
- 45 The upper part of the lever 21 is held in its outer position by the finger 8, secured to the rod 5, causing the upper magazine finger 13 to remain in its withdrawn position; the lower magazine finger 17 being in its inward position supporting the shuttle 4' in the magazine 4, see Fig. 5.
- 50 60 When the shuttle holder 23 is returned to its normal position, the upright bar 22 engages with the lever 21, operating against the finger 8 secured to the rod 5, and causes the upper magazine finger 13 to move inwardly and extend under the shuttles 4' in

the magazine, the lower magazine finger 17 being withdrawn and allowing the shuttle 4' to be dropped upon the shuttle holder 23, see Fig. 4.

The movable shuttle box mounted on the lay 26, has secured to its lower portion two guide rods 27, suitably guided in bearings 28' on a stand 28, see Fig. 1. Adjustably secured to the guide rods 27 are the hubs 29' of the lifter bar 29, which has its lower portion 29" guided in a rocker iron 30. A plate 30', secured to the rocker iron 30, forms the outer part of the guide, said rocker iron 30 has its hub 30" secured to a rod 30'a, supported on the loom side.

70 Loosely mounted on a stud 31" on the lifter bar 29, is the hub 31' of a foot 31, to which is secured, by a bolt 22', the upright bar 22.

75 32 is a stand fast to the loom side 1, and has a hub 32', in which is secured, by a set screw 33', a rod 33, see Fig. 3. The rod 33 has loosely mounted thereon the hub 34' of a locking lever 34, which lever has an open slot or guide way which receives a roll 35, see Fig. 1, loosely mounted on a stud 35' on the upright bar 22, in its inoperative position. The locking bar 34 is held in its outward position by a torsion spring 36, which encircles the rod 33, and has one end secured to the hub 34', and the other end secured to a collar 37, secured to the rod 33 by a set screw 37', see Fig. 3.

80 38 is a stand fast to the driving gear 39 on the bottom shaft 39, is a half coupling 40, see Fig. 9, which has adjustably secured thereto a mutilated gear 41, having a projection 41', upon which projection is secured, by set screws 42, a cam 43, which operates a roll 44' mounted on a stud 44" on a lever 44, which lever is loosely mounted on a stud 45', secured in a stand 45 by a set screw 45". The stand 45 is secured to the main stand 46, fast to the loom side.

85 90 95 100 105 110 115 120 125 130 Loosely mounted on the stud 45' is a second lever 47, see Fig. 1, which lever is held in its outward position by a torsion spring 48, which has one end secured to the hub 47' on the lever 47, and the other end to a collar 49, secured by a set screw 49' on the stud 45. Loosely mounted on the stud 47", secured in a projection 47''' on the lever 47, is a latch lever 50, which lever is held in its outward position by a compression spring 51, see Fig. 1. On an arm 50', forming a part of the latch 50, is secured one end of a giveaway or tension spring 52, the other end of said spring 52 is secured to one end of a connecting rod 53, the other end of the connecting rod 53 is pivotally attached to the lever 54, which lever is secured by a set screw 54' to a rod 55, operated by a feeler, not shown.

90 Secured by a set screw 56' in the hub 46' on the stand 46, is a stud 56, see Fig. 9,

which stud has loosely mounted thereon a sleeve 57, which has secured to its inner end, by keys 58', a cam 58, which has openings 58'' therein. The outer end of the sleeve 57 forms a flange 57'.

Loosely mounted on the sleeve 57 is a mutilated pinion 59, which has projections 59'. The pinion 59 has secured thereto a locking cam 60, which forms part of an outer sleeve 61, having a grooved surface 61' therein, in which surface is guided a roll 62, loosely mounted on a stud 62' fast on the lever 47.

Upon the indication of the filling detector or feeler, not shown, the lever 54 is moved to its outer position, causing the latch 50 through the connector 53 and spring 52, to lock the lever 47 to the lever 44, see Fig. 2, so that the lever 47 will be moved to its inner position as the lever 44 is moved to its inner position, by the cam 43. By the inward movement of the lever 44, the outer sleeve 61, locking cam 60, and pinion 59, are moved to their inner position, the projections 59' engaging with the openings 58'' in the cam 58. As soon as the locking cam 60 reaches the opening 41^a in the gear 41, the pinion 59 is allowed to turn a half revolution, when the gear 41 comes in mesh, the projections 59' engaging the cam 58 with the roll 63, loosely mounted on a stud 63' on a lever 64, which lever is pivotally mounted on a stud 64' secured on the stand 46. The lever 64 has secured in its upper part a stud 65', on which is loosely mounted one end of a rod 65, which rod connects with and unlocks the locking lever 34 turning its open slot toward the track 72 on the lay when in its forward position, see Fig. 2. 66 is an adjustable plate, held in position on the flange 57', by bolts 66'; said plate 66 has secured thereon a stud 66'', on which is loosely mounted one end of a link 67; the other end of the link 67 is connected by a stud 67' to a part 68' of a giveway lever 68. The hubs on the giveway lever 68 are loosely mounted on the stud 69, see Fig. 8, secured on the stand 46. The other part 68'' of the giveway lever 68 has fast thereto an adjustable piece 70, having secured thereon a stud 70', on which is loosely mounted one end of a link 71. The other end of the link 71 is connected to a pin 29'', secured in the sliding portion 29' of the lifter bar 29.

55 During the half revolution of the pinion 59, above referred to, the outer end 68'' of the giveway lever 68 is given a lifting motion, causing the shuttle box 25 to be raised to its upper position, and at the same time causing the roll 35 to pass out of the slot of the locking lever 34 and to follow the adjustable track 72'', secured to the guide stand 72, turning the upright bar 22 on the stud 31'', thereby bringing the shuttle holder 23 in alinement with the lay, so that the

shuttle 4' may be picked through the shed on the backward movement of the lay.

The shuttle box, and spare shuttle holder are constructed substantially as shown and described in U. S. Letters Patent No. 70 614,369, above referred to, having open slotted bottom plates for the picker stick to pass into, and the shuttle box is opened at the back for the discharge of the shuttle, when raised into its inoperative position.

75 There is also fixed on the lay the upright wall 28'', in alinement with the front of the reed, and above the race plate of the lay, said wall 28'' acts as a back for the shuttle box 25, to retain a shuttle in the box and 30 guide its passage across the lay, when the box is in its operative position on the lay, all as substantially described in said patent, No. 614,369.

80 The shuttle box 25, Fig. 2, is shown in its 85 inoperative position above the upright wall 28'', over which the shuttle has been discharged upon the receiving platform 81, and the spare shuttle holder 23 is shown raised in its operative position on the lay. The 90 upright wall 28'' serves as a back for the shuttle holder, to guide the shuttle when picked across the lay.

A tension spring 73 has one end secured to an arm 29^a of the lifter bar 29, and its other 95 end secured to an arm 31^a on the foot 31, and is used to return the shuttle holder 23 to its inoperative position.

74 is a tension spring attached at one end to a stand 75, fast to the loom side, and at 100 its other end to a stud 75', see Fig. 8, on a part 68'' of the giveway lever 68. Loosely mounted on the stud 64' are the hubs 76' and 77' of the levers 76 and 77, forming the give-way lever.

78 is a compression spring encircling a stud 78', and acts to hold the two levers 76 and 77 together. The levers 76 and 77 are operated by a stud 79, secured in the inner part 68^b of the giveway lever 68, and inserted between the levers 76 and 77, see Fig. 8.

115 Secured in the outer end of the lever 77 is a stud 77'', upon which is loosely mounted one end of the connector 80, which has its other end adjustably secured in a rod head 80', loosely mounted on a stud 81', secured to the receiving platform 81, which platform is pivotally mounted on the rod 82' on the stand 82 fast to the loom side 1, and holds the receptacle 83 for the substantially exhausted shuttles. The lever 77 is moved to its downward position, through the operation of the giveway lever 68, thereby placing the lever 81 in its normal position to receive the shuttles, see Fig. 2. These operations are performed on the backward movement of the lay, and on the forward movement of the lay the pinion 59 is given another half revolution, thereby completing 120 125 130

the operation; and returning the parts to their normal position.

A protector rod 84, see Figs. 11, and 12, is mounted in a hub 85' on the stand 85 secured to the lay. Secured to the outer end of the protector rod 84, by set screws 86, is the hub 87' of a stand 87. Pivotally mounted on a stud 87" on the upper part of said stand 87, is a shuttle binder finger 88 which has at its lower end an outwardly extending portion 88'. The finger 88 is held in its upright position, as shown in Fig. 11, by a compression spring 89, bearing at one end against the finger 88, and having its other end extend in a recess in the stand 87.

A stand 90, having an upright portion 90', is secured to the lifter bar 29, and when the shuttle box 25 is raised to eject the shuttle, as shown in Fig. 12, the upright portion 90' of the stand 90, moves the finger 88, against the action of the compression spring 89; by this operation the filling thread from the shuttle, having its free end held in a clamp 91 mounted on the breast beam 1', see Fig. 3, is allowed to pass freely over the finger 88, and into the fabric being woven, the end of the filling thread being severed adjacent the selvage of the fabric, and leaving the end attached to the clamp 91. A torsion spring 92 encircles the protector rod 84, and has one end secured to the boss 93' on the stand 93, and its other end secured to a collar 94 on the rod 84 by a set screw 94'. The spring 92 acts to hold the upper end of the finger 88 in engagement with the shuttle binder 25', and also to turn the protector rod 84 to its normal position, after it has had a partial rotation.

The operation of our improvements is briefly as follows:—When the lay is moving backward, after the detection of the near exhaustion of filling in the active shuttle, the actuating lever 44 being in its outward position, as shown in Fig. 9, the latch 50, carried on the lever 47, engages with the lever 44, as shown in Fig. 2, and as the lay reaches its backward position, the pinion 59 is moved by the lever 47 into position to be engaged by the driving gear 41, and turned one-half a revolution, carrying the crank 66" downward during the next forward movement of the lay. As the pinion 59 commences to turn, the cam surface 58, carried by the pinion 59, shown enlarged in Figs. 9 and 10, moves the lever 64 outward, and through the connecting rod 65, swings the locking lever 34 from its normal position in Fig. 1, to the position shown in Fig. 2, being a preliminary movement, to bring the spare shuttle holder 23 out from under the magazine, and the continued movement of the pinion 59, as the lay reaches its forward position turns the crank 66" downward, and raises the end of the giveaway lever 68, lifting the rod 29, connected with the shifting

shuttle box 25, and the spare shuttle holder 23, raising the shifting shuttle box 25 to an inoperative position, and the spare shuttle holder 23 to an operative position on the lay, at which time the lay has moved partly 70 backward, and the picking of the spare shuttle across the lay occurs as the lay reaches its backward movement, at which time also the exhausted shuttle in the shifting shuttle box 25, which is raised above the 75 stationary wall 23", is discharged by its momentum upon the receiving platform 81, see Fig. 2, and is arrested by the fixed shoulders 83' on the receptacle 83, which shoulders act to align the shuttle with the receptacle, and 80 then the shuttle is raised above the shoulders 83' on the receiving platform 81, through the connecting rod 80 by the lever 77, which is operated by the movement of the lever 68 as it is moved up and down, and the shuttle 85 slides down the inclined surface of the receptacle 93 to its lower end where it may be removed or discharged.

When the levers 44 and 47 are engaged by the latch 50, and have been moved into operative position by the grooved cam surface 43 which cam surface is shown in Fig. 9, they are held in locked position by the guide 50^a, above the latch 50, until said grooved cam has made a complete revolution, and 90 moved said levers outward with the latch 50, from under the guide 50^a, and permits the unlocking of said levers. During this engagement of the levers 44 and 47, and while the shuttle has been picked to the opposite 100 end of the lay, and as the lay is moving forward again, the other lobe on the mutilated gear 41, engages and turns the pinion 59 another one-half turn, moving the crank pin 66" to its upper normal position, and re- 105 turning the shifting shuttle box 25 and the spare shuttle holder 23 to their normal positions, with the locking lever 34 moving the spare shuttle holder 23 under the magazine, as the roll 63 on the lever 64 passes into the 110 depression in the cam surface 58, all of which is performed during one revolution of the grooved cam 43, and while the levers 44 and 47 are locked under the bar 50^a. The giveaway lever 68 is adapted to release the 115 shifting shuttle box from the movement of its actuating crank, if the shuttle should fail to be properly positioned in the shuttle box, whenever a change of shuttles is about to take place.

The two parts of the levers 76 and 77 form a giveaway lever for moving the receiving lever 81 to release said lever from its actuator, if a discharged shuttle is not properly landed on the platform.

When the spare shuttle holder 23 is moving out from under the magazine, the lower end of the lever 21 follows said holder, and moves the retaining fingers 13 out from under a series of shuttles 4' in the magazine 4, 130

at the same time moving inward immediately above the normal position of the spare shuttle holder 23, the finger 17, which receives the shuttle supported on the fingers 13 as it 5 drops, and the fingers 13 are fully withdrawn, and when the spare shuttle holder 23 is moved in under the magazine 4, it contacts with the end of the lever 21, and moves the finger 17 out from under the shuttle, and 10 allows it to drop upon the spare shuttle holder 23, and at the same time moves the fingers 13 under the shuttle above, and prevents it from dropping.

It will be understood that the details of 15 construction of our improvements may be varied if desired.

Having thus described our invention, what we claim as new and desire to secure by Letters Patent is:—

- 20 1. In an automatic shuttle replenishing loom, a lay, a movable shuttle box carried thereon, a rod to move said shuttle box, a magazine on the breast beam for a supply of spare shuttles, a spare shuttle holder normally at rest under the magazine, and having 25 connections to the shuttle box rod, a locking lever in operative position with reference to said connections, whereby upon the indication of the substantial exhaustion of 30 filling in the active shuttle, to move said spare shuttle holder from under the magazine, and means to move said shuttle box and said holder upward on the lay, with the shuttle holder to an operative position, and 35 the shuttle box to an inoperative position.
2. In an automatic shuttle replenishing loom, a magazine for spare shuttles, a shuttle holder under the magazine, and a shuttle shifting mechanism, having means comprising 40 a cam, a lever moved by it, a locking lever actuated by said lever to give a preliminary movement to the shuttle holder from under the magazine, and means to move the shuttle holder into operative position.

- 45 3. In an automatic shuttle replenishing loom, a magazine for spare shuttles, a spare shuttle holder under the magazine, a shuttle on said holder, a shuttle shifting mechanism, having means comprising a cam, a lever moved by it, a locking lever actuated by said lever to move the spare shuttle holder from under the magazine, preparatory to moving it into operative position on the lay, and after the shuttle is picked across the lay 50 returning the spare shuttle holder to its normal inoperative position under the magazine.

- 55 4. In an automatic shuttle replenishing loom, a magazine for spare shuttles, a spare shuttle holder to receive a shuttle from the magazine, a locking lever to hold said shuttle holder normally under said magazine, and means to move said lever, when indicated, to move the shuttle holder out from 60 under the magazine.

5. In an automatic shuttle replenishing loom, a magazine for spare shuttles, a shuttle shifting mechanism, comprising means, comprising a cam, a lever moved by it, a locking lever actuated by said lever, upon 70 indication, to move the spare shuttle holder out from under the magazine, and move it upward into operative position on the lay, and also to move the shuttle box into an inoperative position during one pick of 75 the loom, and during the next pick, returning said shuttle holder and shuttle box to their normal positions, with the shuttle holder under the magazine.

6. In an automatic shuttle replenishing 80 loom, a receiving platform for discharged shuttles, a shoulder or shoulders, extending above the platform to arrest the shuttles in an alined position, and an inclined receptacle for the shuttles to move on, when said 85 shoulder or shoulders are in an inoperative position relative to the shuttles and means for raising said platform above said shoulder or shoulders.

7. In an automatic shuttle replenishing 90 loom, a receiving platform for discharged shuttles, a shoulder or shoulders elevated above the platform to arrest the shuttles in alined position, an inclined receptacle to receive the released shuttles, and means to 95 raise said platform above said shoulder or shoulders.

8. In an automatic shuttle replenishing loom, a lay, a magazine for spare shuttles, a pivoted locking lever, having an open 100 slot therein, a movable bar carrying a spare shuttle holder, and a roll thereon, said roll movable in a slot of the locking lever, whereby said locking lever may be turned to move the shuttle holder under the magazine into 105 an inoperative position, or it may be turned to guide the shuttle holder into an operative position on the lay.

9. In an automatic shuttle replenishing 110 loom, means to change a shuttle when the filling in said shuttle is exhausted, or substantially exhausted, a protector rod, attached to and movable with the lay, a binder finger pivotally mounted, and connected with said protector rod, said binder finger 115 movable on its pivot independent of said rod, and normally bearing at one end against the shuttle binder, and means, connected with the shuttle changing mechanism, to move said finger on its pivot and allow the filling from the new shuttle to pass over said finger, when said shuttle is picked from the shuttle binder.

10. In an automatic shuttle replenishing 120 loom, means to change a shuttle when the filling in said shuttle is exhausted, or substantially exhausted, a protector rod attached to and movable with the lay, a pivotally mounted binder finger mounted on 125 said rod, and movable on its pivot independ- 130

ent of said rod, and normally bearing at one end against the shuttle binder, and means, connected with the shuttle changing mechanism, to move said finger on its pivot, and 5 allow the filling from the new shuttle to pass over said finger when said shuttle is picked from the shuttle holder, and means

to return said finger to its normal position, bearing at one end against the shuttle binder.
